SIGNAL SWITCH

Edward P. Poore and Robert P. Klotz,
Sandusky, Ohio

Application May 23, 1946, Serial No. 671,692

1 Claim. (Cl. 200—1)

1

This invention relates to improvements in a signal device of the type adapted to translate a plurality of initiating indicia into a plurality of corresponding but different exhibited signals.

An object of the present invention is to provide a signal device as exemplified by the flashing of continental code signals for various letters of the alphabet consequent to the pushing of buttons or the like bearing indicia of the letters of the alphabet.

Another object of the present invention is to provide novel means for carrying out the above described functions by the use of very simple apparatus which does not necessitate large numbers of wires as in other devices known to us.

Other objects and advantages of the present invention will be apparent from the accompanying drawings and specification, and the essential features thereof will be set forth in the appended claim.

In the drawings,

Fig. 1 is a general elevational view of the entire apparatus;

Fig. 2 is an enlarged fragmental sectional view taken along the line 2—2 of Fig. 1;

Fig. 3 is a fragmental sectional view taken along the line 3—3 of Fig. 2;

Fig. 4 is an enlarged top plan view taken at the right-hand end of the right-hand piece of equipment of Fig. 1, and with the cover removed to more clearly show the parts;

Figs. 5 and 6 are sectional views taken along similarly numbered lines of Fig. 4;

Fig. 7 is a view similar to Fig. 4 but showing a modified form of construction;

Fig. 8 is a sectional view taken along the line 8—8 of Fig. 7;

Fig. 9 is a diagrammatical view showing the wiring of either form of our device; while

Fig. 10 is a view similar to the left-hand portion of Fig. 1 but showing a modified arrangement for displaying the signals.

Our device is applicable for use as a toy, for actual use in signaling, or for use in instruction in learning the signal code. Other uses of our invention will be referred to at the end hereof.

In the device of Figs. 1 to 6, a battery case 11 houses batteries for operating the device, or other sources of electricity may be used, as will later appear. Mounted on the top of the battery case is a tower 12 carrying signal lights numbered 13 to 19 inclusive. In front of the lights is a housing 20 which may be translucent or transparent and divided in sections for the separate lights, if necessary or desirable.

2

For initiating the signals, we provide a case 21 upon which appear a series of buttons 22 for initiating the signals and carrying a series of indicia 23, one for each button. The relatively small number of connecting wires necessary between the box 11 and the case 21 are housed in the electric cables 24 and 25 which connect the two parts of the device. Obviously, these cables may be of any length required, as the signal may be produced at any distance desired from the housing 21 where the signal is initiated.

Our device will be described for the purpose of flashing the continental code upon the pressing of the buttons 22, although other uses of our invention will occur to those skilled in this art. For this purpose, the lights 13, 15, 17 and 19 are arranged to represent dots in the code, and for this purpose, we have utilized red lamps. The lights 14, 16 and 18 are utilized to represent dashes in the code, and for this purpose, we have used white lights, although another manner of differentiating the dots and dashes will be described later. Referring to Fig. 2, it will be noted that the box 11 and the tower 12 are of insulating material so as to electrically insulate the working parts. On one face of the tower 12 is mounted a plate 26 of electrically conductive material, and the base of each of the lights 13 to 19 inclusive is screwed into a suitable opening in the plate 26, as clearly indicated in Fig. 2. The other electrical connection for operating the lamp is exposed at the base of the lamp thimble, such as those indicated at 18a and 19a of Fig. 2. For each lamp, a spring finger 27 is provided having one end engaging the lamp contact, such as 18a or 19a, and having the other end secured to the insulating material of the tower as by a screw 28. A separate electrical connection for each lamp is provided, as indicated at 29 on Fig. 2. Only three of these wires are shown for the sake of clearness, although, obviously, seven are provided. Each wire 29 is secured beneath one of the screws 28 to complete the electrical connection to the lamp. The wires 29 pass downwardly through an opening 30 in the box 11 and are then led to one of the cables 24 or 25. Obviously, the number of these cables provided is a matter of choice, but in the present instance, having eight wires to connect, we have used two cables, each housing having four wires. It is immaterial which wires are in the various cables, so long as they are properly connected at the terminal ends of the wires.

The electrical means for operating the illustrated form of our device comprises one or more

batteries 31 in the box 11. In the present instance, we have utilized four such batteries having one terminal connected with a flat spring conductor bar 32 in the bottom of the box, and another terminal connected to a similar conductor bar 33 at the top of the box. These bars connect the batteries in parallel. A jumper wire 34 connects the conductor bar 33 electrically with the plate 26. A wire 35 connects the conductor bar 32 with a trunk bus bar in the housing 21, as will presently appear.

The equipment in housing 21 will be most clearly understood from Figs. 4, 5 and 6. This housing is preferably of electrically insulating material so that all of the parts will be properly insulated from each other. Extending lengthwise of the housing along the inside face of the bottom thereof, we provide eight bus bars including a trunk bus bar 36, and light-controlling bus bars 37 to 43 inclusive. The wire 35 is connected to the trunk bus bar 36. The wires 29 are connected for the lamps indicated respectively, as follows: 13 to 37, 14 to 38, 15 to 39, 16 to 40, 17 to 41, 18 to 42, and 19 to 43.

Where the alphabet from A to Z is to be flashed on the signal lamps, we provide 26 control bars marked 44, and each of these bars is operated by a control button 22 located centrally thereof. Each bar 44 lies just beneath the cover 21a of the housing 21 with its opposite ends resting on helical springs 45 which urge each bar 44 upwardly or away from the bus bars. The buttons 22 extend through suitable openings in the top 21a of the housing. The indicia 23 are located adjacent their corresponding buttons on the top cover.

Means is provided on each bar 44 to flash the proper arrangement of lights 13 to 19 inclusive when the bar 44 representing any letter of the alphabet is depressed. For this purpose, a plurality of spring fingers 46 are snapped onto the bars 44, preferably in grooves 44a located in the proper position along each bar corresponding to locations just above the bus bars. These spring fingers 46 are located differently on each of the bars 44, and in correspondence with the code arrangement. For instance, as best seen in Fig. 4, the bar 44x corresponds to the letter X of the indicia 23. This letter in the continental code is represented by the signal dash-dot-dot-dash. It will be noted that there is a spring finger 46a on the bar 44x which overlies the trunk bus bar 36. This is true in the case of each of the letters. In addition, on the bar 44x there are fingers 47, 48, 49 and 50 which respectively overlie the bus bars 38, 39, 41 and 42. These bars serve to energize lamps 14, 15, 17 and 18, respectively, through the circuits as shown diagrammatically in Fig. 9. From the battery 31, the current flows through line 35 to the trunk bus bar 36, then (when bar 44x is depressed) through contact finger 46a and bar 44x through the contacts 47, 48, 49 and 50, in parallel, respectively, to the bus bars 38, 39, 41 and 42, and through the respective wiring connections to lamps 14, 15, 17 and 18, respectively, and through these lamps to the plate 26, and through line 34 back to the battery.

In similar manner, the contact fingers on bar 44y (Fig. 4) are arranged to engage bus bars 38, 39, 40 and 42, so as to produce the signal dash-dot-dash-dot which corresponds to the letter Y in the said code. In like manner, the contact fingers on bar 44z are set to produce a signal dash-dot-dot-dot corresponding to the letter Z. It will now be clearly understood how the entire

alphabet may be produced on the twenty-six bars carrying the general number 44 and corresponding to the indicia printed at 23. The operator has merely to press the selected button 22 and the corresponding signal will be flashed on the lights in the tower 12.

A modification of the above device is shown in Figs. 7 and 8. This modification consists solely in the arrangement of the bars 44' carrying out the functions of the bars 44 of the first described modification. All of the rest of the device is similar to that first described, and similar parts have been given similar reference characters. Each of the bars 44' is of electrically conductive material, such as spring brass, and extends entirely across the width of the housing 21, all of the bars being pivoted on a common shaft 51 which extends along one side of the housing 21, parallel to the bus bars 36 to 43 inclusive. A spring finger 52 is punched out of the material of the bar 44' in the case of each of the bars, to extend down into contact with bus bar 36. This acts not only as a conductor of electricity similar to the fingers 46a first described, but additionally supplies the spring action for raising bars 44' out of contact with the bus bars when the button 22' is released. It will be understood that these buttons 22' extend through the cover of housing 21 and are provided with indicia such as that illustrated at 23 in Fig. 1. Each bar 44' is specially designed to produce a particular letter. For instance, the left-hand bar 44' shown in Fig. 8, corresponds in function to the bar 44y shown in Fig. 4. The fingers 53 are punched out of the material of the bar 44' so as to provide contact with bus bars 38, 39, 40 and 42, so as to light the lights 14, 15, 16 and 18, producing the signal dash-dot-dash-dot representing the letter Y of the code alphabet. In a similar manner, the right-hand bar 44' shown in Fig. 7, is set to produce the signal for the letter Z and each of the other bars, of which twenty-six may be provided, produces one of the letters of the alphabet, as described in connection with the first modification. The form of Figs. 7 and 8 produces the same result as the first described form, but is cheaper to construct.

In Fig. 10, we have shown a further modification which has to do only with the tower 12' which is a substitute for the tower 12 shown in Fig. 1. The rest of the apparatus is exactly like that first described and it will be understood that the tower 12' carries lights similar to 13 to 19 inclusive, back of opaque shields 54 and 55. In this case, all of the lights in tower 12' may be of one color. Each of these shields has a central opening, those in the shields 54 as shown at 54a being in the form of a small dot, while those at 55a in the shields 55 are in the form of an elongated slotted opening producing a visual dash. This tower, when connected with the first described system, will produce signals on the various lamps 13 to 19 inclusive, as they are selected by pressing the different buttons 22. The only difference here is that instead of producing red and white signals indicating dots and dashes, as described in the first modification, the device of Fig. 10 will actually show visual dots and dashes corresponding to the sounds when the code is produced audibly. We find that this modification of Fig. 10 is better for instruction, as the visual signal gives the same impression to the student as the audible telegraph signal, and does not require the mental translation of different colored lights into the dot-dash code, as is true in the device of Fig. 1.

We have described our invention as utilized to

flash an alphabet code, but it will be understood by those skilled in this art that the structure shown might be used to produce other sets of signals not requiring any but the simplest wiring, and not requiring the operator to actually know the code. Instead, all that the operator need do is to press the buttons corresponding to the desired indicia and a signal corresponding to those indicia will be produced at the signal tower.

What we claim is:

In combination, a housing, a plurality of parallel bus bars therein, a plurality of parallel signal bars adjacent and at right angles to said bus bars, spring means at opposite ends of said signal bars and supporting each of them for limited movement toward and away from said bus bars, contact fingers of spring material removably mounted on said signal bars adjacent said bus bars, and each of said contact fingers having a portion adapted to embrace one of said signal bars and

having another resilient portion extending away from said signal bar, and adapted to engage one of said bus bars, whereby said contact fingers may be positioned as desired on said signal bars.

EDWARD P. POORE.
